(No Model.)

P. KESLING.

FENCE LOOM.

No. 372,419.

Patented Nov. 1, 1887.

UNITED STATES PATENT OFFICE.

PERRY KESLING, OF WALTON, INDIANA.

FENCE-LOOM.

SPECIFICATION forming part of Letters Patent No. 372,419, dated November 1, 1887.

Application filed August 23, 1886. Serial No. 211,582. (No model.)

To all whom it may concern:

Be it known that I, PERRY KESLING, a citizen of the United States, residing at Walton, in the county of Cass, State of Indiana, have 5 invented certain new and useful Improvements in Fence-Looms, of which the following is a specification, reference being had therein to the accompanying drawings.

This invention has relation to fence-ma-10 chines; and the object is to provide a simple hand-operated device for twisting the wires composing the strands of the fence after each succeeding picket is arranged within said wires; and the invention consists in certain 15 features of construction, hereinafter described, and particularly pointed out in the claims.

Referring to the drawings, Figure 1 is a side elevation of a strand-twisting machine constructed in accordance with my invention. 20 Fig. 2 is a similar view of the machine in the position it occupies with relation to the fence during the operation of forming a half-twist in the strands thereof. Fig. 3 is a plan with the machine in the position shown in Fig. 1. 25 Fig. 4 is a detail in perspective of the shuttle.

Like letters refer to like parts in all the figures of the drawings.

Let A represent the pickets, and B B' a pair of wires forming one strand of the fence, of 30 which strands there may be as many as desired, the machine in this instance being illustrated as constructed to operate upon three strands simultaneously, so as to produce a half twist or coil of each wire of each strand 35 about the other wire of the same strand between each two of the pickets of the fence.

C represents the main beam of the machine, which is provided with a handle, C', of which there may be more than one, if desired. From 40 the main beam there extends rigidly as many arms D as there are shuttles E, the latter being pivotally mounted on the arms, as at E'. Each of the shuttles may be a solid block pivoted to a side of the arm D, as shown in Figs. 45 1 and 2, and provided with a wire-receiving slot, E², between its end and its pivot, and another wire-receiving slot, E³, formed in its end; or the shuttle may consist of two bars, e e', pivoted, as at E', so as to embrace the end 50 of the arm D and spaced at their free ends by a block, E⁴, arranged between the bars, as

shown in Figs. 3 and 4. In this latter construction the two slots E² are slanted in opposite directions, whereby the unremoved portions E⁵ of each bar serve to retain the wire 55 within the slots. If the slots E² were in one face of a solid shuttle and oppositely inclined and merged in a wire-receiving hole passing through the block, a V-shaped piece would be removed from one face thereof, and thus it 60 would be unsuited for use as a shuttle; but if the shuttle were made of two separated bars and the slots therein were oppositely inclined and arranged on opposite edges of the bars, then it would be necessary to first insert the end of 65 the wire between the bars before it (the wire) could be passed through both slots. Now, by making the shuttle of two parallel separated bars and forming the slots E² at similar (not opposite) edges the wire can be introduced 70 laterally and at any point between its ends. This advantage is furthered by the open end slots, in that the shuttle may be applied at any point on the untwisted strands. In this regard my shuttle is new and capable of use 75 with other means than that shown for oscillating it to form the twist in the strands. On each of the bars D, and extending at right angles thereto, is a gage, D', which rests against the last-inserted picket A during the opera- 80 tion of twisting the strands. In order that the gage shall rest against said picket in all positions assumed by the machine, as herein-after described, the gage may be extended, as 85 shown by dotted lines D², Fig. 3.

This being the construction, the operation is as follows: Taking the machine in the position illustrated in Figs. 1 and 3—that is, with the strand B' passing through the slot or slots E² and the strand B passing through the slot 50 or slots E³—the main beam is moved downwardly and to the left and then upwardly in the direction indicated by the arrow a, which movement causes the shuttles E to oscillate, as indicated by the arrows b c in Fig. 1, (they 95 being brought under the arms D, as shown by dotted lines x, Fig. 2,) the center of movement being substantially in line with the pickets A, whereby the strand B' is thrown over and under the strand B, and the last picket A is 100 secured in position. Another picket is now inserted, the gages placed against the same,

and the beam C is moved downwardly and to the right and upwardly, as shown by the arrow *d* in Fig. 2, which oscillates the shuttles E in the direction shown by the arrows *e,f*, whereby the strand B' is thrown over and under the strand B, so that a half coil or twist is formed between each two of the pickets.

The dotted circle or arrow *g*, Fig. 1, illustrates the path of the wire-containing slots during the first movement of the machine, the path being the same, but in an opposite direction, in the second movement of the machine.

Having described my invention and its operation, what I claim is—

- 15 1. A shuttle for fence-loom, comprising two bars having apertures for a wire and oppositely-disposed slots leading to the apertures, and having a wire-receiving slot in the end of the shuttle, substantially as specified.
- 20 2. A shuttle for fence-loom, comprising two bars provided with wire-receiving slots in

each bar and with a wire-receiving slot or slots in the ends of said bars, substantially as specified.

3. The combination of the beam C, having 25 arms D, and shuttles E, having the oppositely-disposed slots E², forming retaining portions E⁵, the slots E³, and spacing-block E⁴, and the gages D', substantially as specified.

4. A twisting-shuttle for a fence-machine, 30 consisting of two parallel bars and a spacing-block and provided with end slots, E³, and intermediate oppositely-disposed slots E², forming the wire-retaining projections E⁵ in each bar, substantially as specified.

In testimony whereof I affix my signature in presence of two witnesses.

PERRY KESLING.

Witnesses.
